UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 1, 1920, Serial No. 385,651. Renewed May 21, 1927.

My invention relates to mining apparatus.

It has for its object to provide an improved mining apparatus. A further object of my invention is to provide improved means for driving a mining machine truck. A further object of my invention is to provide an improved, rugged, and simplified truck driving means, adapted to be driven by a mining machine carried on the truck, and constructed and arranged in an improved manner enabling the power desired for transport purposes to be obtained and readily controlled.

In the accompanying drawings I have shown for purposes of illustration one embodiment which my invention may assume in practice.

In these drawings,—

Fig. 1 is a side elevation of a mining apparatus equipped with my improvement, the machine being shown in transport position on its truck.

Fig. 2 is a larger plan view of the cooperating truck driving mechanism on the machine and truck, certain parts being broken away to facilitate illustration.

Fig. 3 is a vertical sectional view on line 3—3 of Fig. 2.

In this illustrative construction I have shown a mining apparatus including a truck 1 of low or drop axle construction mounted on wheels 2 and adapted to be propelled over a mine track 3, the truck herein carrying a flexibly fed mining machine 4 adapted to slide on its bottom on a mine bottom during cutting and having improved operative connections hereinafter described whereby when said machine is loaded for transport on the truck the truck wheels 2 may be driven from the mining machine motor. Herein the mining machine is shown as of the construction described and claimed in my Patent No. 1,544,398, granted June 30, 1925. As in a usual construction, a pinion 5 on the rear end of the mining machine motor shaft 6 also drives a flexible feed operating member 7 adapted to cooperate directly with a flexible feeding member and to draw the latter in and move the machine bodily when desired or swing the bar, the member 7 being driven through a usual friction controlled fast and slow feeding mechanism, herein for purposes of illustration simplified and shown as only comprising a fast feed mechanism including a

pinion driven gear 8, bevel pinion 9, bevel gear 10, a friction clutch 11, gears 12, 13, 14 and 15.

In my improved construction, however, the truck driving mechanism is not driven through the friction controlled feeding mechanism, but is instead separately driven directly from the motor and controlled by another friction, herein a larger clutch carried on the truck. Thus, it will be observed that the truck driving mechanism carried upon the machine is enabled to be powerfully, positively, and simply driven at a proper speed and to cooperate with this other friction clutch, in such a manner as thereby to avoid all necessity for providing in the machine feed an objectionably large friction clutch of the character required to transmit sufficient power to the truck, or disturbing the feeding mechanism in any way whatsoever.

Herein, it will be noted that the pinion 5 drives the truck driving mechanism through suitable reducing mechanism, herein operatively connected to the motor at a point between the initial driving gear of the feeding mechanism and the motor in such manner as to be independent of the feeding mechanism. More particularly, the pinion 5 drives a larger gear 16 fixed to a longitudinal shaft 17 journaled at 18 in the motor head 19, and this shaft 17 in turn carries on its rear end a smaller bevel pinion 20 meshing with a cooperating shaft mounted bevel pinion 21 of the same size rotatable on a transverse axis in the side of the machine frame and carrying on its outer end a suitable truck driving member, herein a sprocket 22.

This truck driving member is in turn connected by suitable means, herein in the form of a chain 23, with mechanism on the truck and connected to the truck wheels, this mechanism herein including a larger sprocket 24 rotatably mounted coaxially with a transverse rotary shaft 25 carried on the rear end of the truck. As shown, the sprocket 24 is herein enclosed in a suitable housing 26 carried on the frame and is fixed to a rotatable sleeve 27, which is itself coaxially disposed and rotatable with one of the elements 28 of a large friction clutch 28, 29, whereof element 29 is toggle operated and connectible with a spider 30 keyed to the shaft 25 and engageable with a collar 31.

on the shaft. As shown herein, this adjustable clutch member 29 is adjustable by means of a longitudinally disposed clutch shifting member 32 pivoted at its front end 5 on the truck frame and engageable with lugs on a movable actuating element 33, movable longitudinally of the shaft to control the element 29 and disposed coaxially with the latter on the shaft. This member 33 is herein 10 also provided with a rearwardly extending end pivotally connected at 34 to a transversely disposed lever 35, the latter in turn being pivoted at 36 to form a toggle with an operating handle 37 pivoted at 38 to the 15 frame.

As shown herein, the shaft 25 is also friction controlled by a suitable brake, the shaft herein being provided intermediate its ends with a concentrically arranged shaft 20 brake 39 controlled by a suitable controlling lever 40. Further, the shaft is connected at one or both of its ends with the truck wheels, the shaft carrying on its opposite ends sprockets 41, one or both of which, as 25 desired, may be connected through chains 42 with the wheels 2 on the rear stub axle 43, and through suitable chain and sprocket connections 44, with the wheels 2 on the front stub axle 45. Thus it will be noted that the 30 truck is driven through the shaft 25 and that through the friction clutch and brake on the shaft, the truck movement may be controlled as desired.

In considering more in detail the operation 35 of my improved construction, it will be observed that when the machine is loaded on its truck and the chain 23 is connected to the sprocket 22, the rotation of the motor shaft 6 is transmitted through the pinion 5, gear 40 16, meshing pinions 20 and 21, to the sprocket 22, which is constantly and positively rotated at a reduced speed due to the transmission mechanism employed. Thus, when the chain 23 is connected to the 45 sprocket 24, the clutch element 28 will be constantly rotated. When it is desired to drive the truck, it is then only necessary to move the operating handle 37 in order to actuate its toggle and in turn actuate the clutch shifting lever 33 in such a manner 50 as to cause the member 32 to move longitudinally of the shaft 25 and thereby expand the clutch elements 29 into gripping relation with the clutch element 28, whereupon the shaft 25 will be rotated to drive the sprocket 41 and propel the truck. Due to the provision 55 of the toggle connections for the operating handle 37, it will be observed that the two clutch elements may be practically positively connected if desired at the same time 60 that the speed may at any time be varied through a partial manual release of the members 29. It will also be evident that through the operation of the brake 39 the 65 truck may be further controlled when de-

sired, this brake being operable independently of the clutch mechanism to vary the speed of rotation of the shaft 25 when and as desired.

In my improved construction, it will also be observed that, through the provision of my improved truck driving mechanism on the machine and truck, all necessity for disturbing or re-organizing the feed mechanism on the machine is avoided, at the same time 75 that it is made possible to simplify the mechanism on the truck and to provide a powerful friction controlled drive including a suitably large friction clutch. It will also be evident that through this friction clutch 80 and its cooperating and conveniently located brake mechanism likewise operating upon the transverse truck shaft, the speed of the truck may be readily controlled through their single or joint operations when desired. Attention is also directed to the fact 85 that the construction is both exceedingly simple and rugged, and also well-adapted to be applied to machines of standard construction at relatively small expense. 90

While I have in this application specifically described one embodiment which my invention may assume in practice, it will be understood that this form of same is used 95 for purpose of illustration and that the machine may be modified and embodied in various other forms without departing from its spirit or the scope of the appended claims.

What I claim as new and desire to secure 100 by Letters Patent is:

1. In combination, a mining machine 105 slideable on its bottom on a mine bottom during cutting and having feeding mechanism thereon including a driving motor, a truck carrying said mining machine, truck driving mechanism operatively connected to said motor wholly independently of said feeding mechanism and including a friction clutch on said truck controlling truck movement, 110 and an independently operable brake carried on said truck and controlling truck movement.

2. In combination, a mining machine 115 slideable on its bottom on a mine bottom during cutting and including a motor and feeding mechanism driven thereby through a friction clutch, a truck carrying said machine, truck driving mechanism positively driven by the same end of said motor driving said 120 feeding mechanism but wholly independently of the latter and including a friction clutch controlling truck movement, and an independently operable brake on said truck controlling truck movement.

3. In combination, a mining machine 125 slideable on its bottom on a mine bottom during cutting and having feeding mechanism thereon including a driving motor, a wheeled truck carrying said mining ma- 130

- chine, truck driving mechanism operatively connected to said motor wholly independently of said feeding mechanism and including a wheel driving shaft on said truck and a friction clutch controlling the rotation of said shaft, and a truck brake acting on said shaft.
4. In a truck driving mechanism, a wheeled truck frame, a truck driving shaft thereon, a wheel driving sprocket on said shaft, a clutch member disposed coaxially with said shaft, and rotatable thereon, a shaft driving member rotatable with said clutch member, a cooperating clutch member disposed coaxially with said shaft and rotatable therewith, and operating means including a toggle for operatively connecting said clutch members.
5. In combination, a mining machine having a longitudinally extending motor shaft, and feeding mechanism operatively connected thereto and driven thereby including a feed operating member adapted to cooperate directly with flexible feeding means and a feed train for driving said feed operating member, said motor shaft carrying a pinion driving said feed train, a wheeled truck adapted to receive said mining machine for transport, and truck driving mechanism driven by said motor and connected to the truck wheels including a laterally extending truck driving member and operative connections between the same and said motor shaft including a gear meshing with said pinion carried on said motor shaft, said truck drive, including said gear, being wholly independent of said feeding mechanism.
6. In combination, a mining machine having a longitudinally extending motor shaft, a pinion on said shaft, and feeding mechanism operatively connected to and driven by said motor shaft including a feed train driven by said pinion and a feed operating member adapted to cooperate directly with flexible feeding means driven by said feed train, a wheeled truck adapted to receive said mining machine for transport, and truck driving mechanism driven by said motor and connected to the truck wheels including a laterally extending truck driving member and operative connections between the same and said motor shaft including a spur gear driven by said motor shaft pinion and independent of the feed train and bevel gearing connected to said spur gear and to said laterally extending member.
7. In combination, a mining machine slideable on its bottom on the mine bottom during cutting and having a laterally extending truck driving member, a wheeled truck for supporting said mining machine during transport, and truck driving mechanism between said laterally extending member and the truck wheels including a transverse truck driving shaft on said truck, a flexible connection between a point intermediate the ends of said shaft and said laterally extending member, flexible connections between the opposite ends of said shaft and the truck wheels, a friction clutch on said shaft for connecting said connections and controlling truck movement, and an independently adjustable manually controlled brake acting on said shaft and disposed on the opposite side of said friction clutch from the connection to said laterally extending member.
8. In combination, a mining machine of the type having a frame slideable on its bottom on the mine bottom and a motor shaft extending longitudinally thereof, and feeding mechanism operatively connected to said motor shaft and driven thereby, a wheeled truck adapted to receive said mining machine for transport, and truck driving mechanism driven by said motor shaft and connected to the truck wheels including a truck driving member journaled on said frame and projecting laterally therefrom, operative connections between said motor and said member disposed within the frame and including a gear driven by said motor shaft, branched driving connections between said gear and said truck driving member and said feeding mechanism, said connections between said gear and said truck driving member including intermeshing gearing wholly independent of the feeding mechanism beyond said gear, and operative connections between said truck driving member and the truck wheels.
9. In combination, a mining machine of the type having a frame slideable on its bottom on the mine bottom and a motor shaft extending longitudinally thereof, and feeding mechanism operatively connected to said motor shaft and driven thereby, a wheeled truck adapted to receive said mining machine for transport, and truck driving mechanism driven by said motor shaft and connected to the truck wheels including a truck driving member journaled on said frame and projecting laterally therefrom, operative connections between said motor and said member disposed within the frame and including a gear driven by said motor shaft, branched driving connections between said gear and said truck driving member and said feeding mechanism, said connections between said gear and said truck driving member including intermeshing gearing wholly independent of the feeding mechanism beyond said gear, and operative connections between said truck driving member and the truck wheels.
10. In combination, a mining machine of the type having a frame slideable on its bottom on the mine bottom and a motor shaft

extending longitudinally thereof, and feeding mechanism operatively connected to said motor shaft and driven thereby, a wheeled truck adapted to receive said mining machine for transport, and truck driving mechanism driven by said motor shaft and connected to the truck wheels including a truck driving member journaled on said frame and projecting laterally therefrom, operative connections between said motor and said member disposed within the frame and including a gear driven by said motor shaft, branched driving connections between said gear and said truck driving member and said feeding mechanism, said connections between said gear and said truck driving element

being wholly independent of the feeding mechanism beyond said gear, and said connections between said motor driven gear and said truck driving member including a horizontal transverse shaft journaled on the side of the machine frame and to the outer end of which said truck driving member is connected, a bevel gear disposed within said frame and secured to the inner end of said shaft, and a bevel gear meshing with said bevel gear, and operative connections between said truck driving member and the truck wheels. 20 25

In testimony whereof I affix my signature.

MORRIS P. HOLMES.
